UNITED STATES PATENT OFFICE.

JAMES S. ANDREWS, OF KALAMAZOO, MICHIGAN.

WHEEL-CULTIVATOR.

SPECIFICATION forming part of Letters Patent No. 280,436, dated July 3, 1883.

Application filed October 12, 1882. (No model.)

To all whom it may concern:

Be it known that I, JAMES S. ANDREWS, of Kalamazoo, in the county of Kalamazoo and State of Michigan, have invented certain new and useful Improvements in Wheel-Cultivators; and I do hereby declare the following to be a full, clear, and exact description of the invention, such as will enable others skilled in the art to which it pertains to make and use the same.

My invention relates to wheel-cultivators; and it consists in rigidly attaching the cultivator-beam to the axle or other part of the carriage, so that vertical movement of the beam is prevented; in pivotally attaching the tooth-bar to the beam; in mechanisms for raising or lowering the teeth, and in parts and combination of parts that will be more fully hereinafter described and claimed.

20 In the drawings, Figure 1 is a view in perspective of a wheel-cultivator constructed according to my invention. Fig. 2 is a side view of the cultivator, showing the mechanism for raising and lowering the teeth. Fig. 3 is a perspective view of the ratchet-brace, showing its construction and its pivotal connection with the tooth-bar. Fig. 4 is a detached view in perspective of the castings used in attaching the beam to the axle and the means employed 25 for the horizontal movement of the cultivator-teeth.

30 In the said drawings, A is the axle, which is represented as being raised in the center, so as to sufficiently elevate the rear portion of the pole B. This is the old and well-known construction common to many machines of this character.

To the horizontal portions of the axle A' A', to which the wheels are directly attached; and, 35 between the wheels and the upright portions A² A², I attach the cultivator-beams; and instead of pivoting the beams to the axle or at a point adjacent thereto in such a manner as to permit vertical movement of the beam, I rigidly 40 attach the beam to the axle or interpose mechanism by which lateral movement of the beam only is permitted, preferably by making that portion of the axle angular and clamping thereto the casting or head C. (Shown in detail in Fig. 4.) This casting or head C is made in two parts, each part provided with a recess;

45 C', adapted to fit and contain the axle. When in position, a second casting, D, Fig. 4, is provided with an eye, D', by means of which it is attached to the head C and lateral motion permitted, but vertical motion prevented. This casting D is also provided with two fingers, D² D², to which are permanently attached the two arms E E, constituting the beam of the cultivator. These arms are preferably made 50 of bars of wrought-iron or steel, and are connected at the rear end by the ratchet-brace F, Fig. 3. This ratchet-brace F is made in two parts, as shown in the drawings, having a space between the parts to permit the free passage 55 of the lever or handle G. One part of the brace is also toothed upon its upper face, and forms an arc of a circle having for its center the point G', where the handle is pivoted to the beam.

60 The tooth-bar H consists of two pieces, between which are secured the upper ends of the teeth J. These teeth are preferably bent in different shapes, so that while they are attached to the same head their points travel in separate 65 lines, as shown in Fig. 2. The pieces forming the tooth-bar are held together by screw-bolts, and the teeth are readily adjusted for depth of cut by raising or lowering them in the tooth-bar. The tooth-bar is pivotally connected with 70 the beam at K K, Fig. 3.

75 The handle or lever G, which is preferably made in the shape of a plow-handle, is pivoted to the beam at G', while its lower end is connected by a rod, L, with the tooth-bar, so that as the handle is raised the points of the teeth are thrown backward and more or less out of the ground, depending upon the height to which the handle is raised. In order that the handle may be secured in any position desired, 85 it is provided with a spring-pawl, M, adapted to engage with the teeth of the ratchet-brace F.

Having described the construction, the operation of my invention is as follows: To adjust the teeth to the depth of cut desired the machine may be placed upon any even surface, as a barn-floor. The wheels may be placed upon blocks as high as the desired depth of cut. The bolts which hold the two pieces together of which the tooth-bar H is composed 95 are loosened and the points of all the teeth permitted to rest upon the floor. The bolts 100

are then tightened and the cultivator is ready for work. When not in use, as being drawn to the field, the handles should be elevated or thrown forward, which will throw the teeth 5 rearwardly and out of the ground.

When in position for use, the handles and with them the teeth are lowered to their proper position, and as by my improved construction the beam is rigid, so far as vertical movement 10 is concerned, the teeth are kept at the desired depth. If any single tooth should come in contact with an obstacle, it would spring back and clear itself without disturbing the other teeth of the gang. The beams permitting of horizontal movement, the operator can easily, by 15 manipulating the handles G, avoid injury to the plants he may be cultivating.

What I claim is—

1. In a wheel-cultivator, the combination, 20 with the angular axle, of the two-part head C, having the rearwardly-projecting ears, one

above the other, the bifurcated casting D, having the flat eye D', pivoted between said ears, and the two-part cultivator-beam secured to the prongs of said casting, respectively, substantially as specified. 25

2. The combination of the two - part cultivator-beam, the tooth-bar pivoted to the two parts thereof at its upper edge, the handle pivoted between the two parts of the beam and 30 having its lower end connected with the lower edge of the tooth-bar, and means for retaining said handle as adjusted, substantially as described.

In testimony whereof I have signed my name 35 to this specification in the presence of two subscribing witnesses.

JAMES S. ANDREWS.
